UNITED STATES PATENT OFFICE.

EDWIN L. RELLER, OF PORTLAND, OREGON, ASSIGNOR TO THE DUCO ADDING MACHINE COMPANY, OF ST. LOUIS, MISSOURI, A CORPORATION OF MISSOURI

MECHANISM FOR POSITIONING THE ZERO TYPES OF ACCUMULATOR WHEELS FOR PRINTING.

1,123,007.

Specification of Letters Patent. Patented Dec. 29, 1914.

Original application filed October 16, 1911, Serial No. 654,982. Divided and this application filed January 26, 1914. Serial No. 814,323.

To all whom it may concern:

Be it known that I, EDWIN L. RELLER, a citizen of the United States, formerly residing at the city of St. Louis, State of Missouri, but now residing at the city of Portland, in the county of Multnomah and State of Oregon, have invented certain new and useful Improvements in Mechanisms for Positioning the Zero Types of Accumulator 10 Wheels for Printing, (the present application being one divided out of that filed by me October 16, 1911, Serial No. 654,982,) of which the following is a specification.

This application is a division and continuation of one filed by me October 16, 1911, Serial No. 654,982.

The present invention relates to improvements in calculating machines and is more especially applicable to calculating machines 20 of the type embodied in the pending application of Edwin A. Reed, Edwin L. Reller, William L. Swift, and Albert J. Meier, filed April 3, 1911, Serial No. 618,655; the present improvements being directed particularly to mechanism for positioning the zero types of the accumulator wheels in position for printing.

The object of the present invention is to provide, in a calculating machine, means 30 whereby the printing wheels of the accumulator are automatically set to print zeros in all columns to the right of the column containing the selected numeral.

In the accompanying drawings forming 35 part of this specification, in which like numbers of reference denote like parts wherever they occur, Figure 1 is a longitudinal vertical sectional view taken centrally through the accumulator, indicating the manner in 40 which the accumulator actuating bars cooperate therewith; Fig. 2 is a sectional view on the line 2-2, Fig. 1; Fig. 3 is a left side elevation of the accumulator; and Fig. 4 is a right side elevation of the accumulator.

The present embodiment of this invention is, as previously stated, applicable particularly to calculating machines of the type disclosed in the above-identified application, 50 and in the drawings illustrating such embodiment, the main operating elements are

represented as constituted by a series of bars 1, which are themselves actuated from the item-printing mechanism (not shown), so as to transmit their movements to the total-printing wheels 2 of the accumulator. There is one of these bars 1 for each printing wheel 2, and at the left-hand side of each bar is mounted a shiftable plate 3, the movement of said plates being largely concerned, however, with the item-printing mechanism, which forms no part of the present invention. Accordingly the operation of the plates with respect to that mechanism requires no description beyond the fact that the plates are guided relatively to their respective bars by means of pins 4, which are located at the forward ends of said plates and work freely in longitudinal slots 5 in said bars.

The upper forward edge of each bar 1 is formed with a rack 6 to cooperate with the respective printing wheel 2 of the accumulator, and the lower edge of each plate 3 is provided with a forwardly directed hook 7, the latter being utilized to engage and elevate a cross-bar 8 when the plate is moved forwardly and subsequently raised, as hereinafter described. This cross-bar connects a pair of arms 9 borne by a transverse shaft 80 10, which is suitably journaled in a pair of supports 11, the free front ends of said arms being formed with upwardly directed hooks 12 for the purpose hereinafter described, which hooks are normally held in lowered 85 position by a spring 13 or a plurality of such springs.

The forward ends of the rack bars 1 and the cooperative plates 3 normally rest upon a supporting cross-member 14, which is arranged at the entrance of the accumulator and has a comb 15, through which the rack bars and plates operate, whereby such parts are maintained in proper spaced relation. A jack 16 is located immediately adjacent 95 to the support 14, the jack embodying a pair of end members 17, which members are connected by and rigidly mounted on a cross-bar 18. Vertical movement and a limited extent of forward and backward movement are permitted the upper portion of the jack by a link 19, which is pivotally cou-

- nected to one of the main side plates 20 of the accumulator frame or casing at the point 21, the opposite end of this link being slotted and connected to the jack by the pin 22.
- 5 The cross-bar 18 is secured to a pair of arms 23, each of these arms being pivotally connected at 24 to the main side plates. The free ends of the arms 23 have extensions 25 adapted to bear upon the laterally turned 70 upper ends 26 of a pair of supporting detents 27, these detents being pivoted at 28 to the main side plates 20 and being yieldingly held in position to retain the jack elevated by springs 29, one end of each of 75 these springs being attached to an eccentrically arranged eye 30 on the respective detent, while the opposite end of the spring is attached to the adjacent end member of the jack, whereby the jack will be pulled 80 down after being released by the detents. The detents are disengaged from the jack when the upper portion of the latter is rocked toward the right, Fig. 1, the disengagement being effected by the prolongation 85 31, which bears against and rocks the respective detent. The upwardly directed hooks 12, however, when elevated, engage the upper part of the jack and thereby lock the latter in elevated position.
- 30 The toothed actuating wheel 32 for each printing wheel 2 is located directly above, but in normal disengaged relation to the rack teeth 6 of the respective rack bar. The printing wheels and their actuating wheels 90 32 are mounted to revolve on a common shaft 33, and the periphery of each printing wheel carries a circular row of type faces 34 bearing consecutively arranged numerals, and, also, a type face 35 bearing a zero character. A series of pawls 36, one for each wheel 32, is rotatably mounted on cross-rod 37, and each pawl is held in engagement with the respective wheel 32 by the spring 38, so as to prevent same from spinning and, also, 95 to center the respective wheel 2 for printing, the nose of said pawl normally occupying a position between two teeth of the wheel 32, in order to allow same to be rotated rearwardly to set the zero type face of its printing wheel in printing position in the manner hereinafter described.
- One of the arms 23 of the jack is part of a bell-crank, the other arm 39 of which has a nose 40 arranged to coöperate with a cam 55 41 borne by the rock-shaft 42, the latter being operatively connected with and actuated by the main operating element of the calculating machine. By this arrangement, the cam 41 effects the raising of the jack 16 in the usual manner. The accumulator, also, embodies a set of members 43, which are adapted to automatically set the printing wheels of the accumulator in zero-printing 110 position, there being one of these members 60 for each printing wheel. One end of each of these members has a longitudinal slot 44 to receive the cross-rod 45 while the opposite end thereof is formed with an upwardly directed projection or tooth 46, which is adapted to enter a wedge-shaped 70 notch 47 formed in the periphery of the respective printing wheel. Each member is provided at an intermediate point with a locking shoulder 48 and, also, with an angular slot 49, the latter receiving a pin 50 75 borne by the arm 51 of a bell-crank, such arm having a depending projection 52, which coöperates with a comb 53, whereby such parts are maintained in proper spaced relation. A tension spring 54 normally acts 80 to pull each member 43 to the right, Fig. 1, the other arm 55 of the bell-crank associated with that member, which is pivoted on the cross-rod 45, being engaged by a tension spring 56, which normally tends to lift the 85 arm 51. Each member 43 is formed with a shoulder 57, which is adapted to be engaged by the upper transverse member of the cradle 58, which, when rocked toward the left in the usual manner, effects the restoration 90 to normal position of all of the released members. A latch 59 is provided for each member 43, and these latches are pivotally mounted at their forward ends on the cross-rod 60 and are formed with shoulders 95 61 arranged to coöperate with the shoulders 48 of the respective members, when the latches are lowered, thereby preventing forward movement of such members under the action of their springs 54. The rear end of 100 each latch is provided with a laterally turned projection 62, which is adapted to bear upon the top of the respective plate 3, the latter when lowered and resting upon the support 14 permitting the latch to remain in locked engagement with its respective member 43. When such plate is elevated in the manner hereinafter described, the latch will be elevated and, in consequence, disengaged from its respective 110 member 43, thereby permitting the latter to move forwardly under the influence of its spring 54, the projection 62 on such member then acting to turn the respective printing wheel sufficiently to bring the zero type 115 face 35 thereon into printing position. Continued movement of the member 43 causes its projection to become disengaged from the printing wheel. The latches 59 are held in locking position by springs 63.
- 120 The operation of the mechanism is as follows: The entering of the items is accomplished in the same manner as in the calculating machine described in the aforesaid application, Serial No. 618,655, that is to say, by depressing and rotating the finger pieces or sectors, and when each finger piece or sector is depressed or rotated, the rack bar 1, which is operatively connected thereto, moves forwardly into the accumulator, 125 130

it being understood that the rack teeth 6 of the bar do not engage the respective toothed actuating wheel 32 when the rack bar so enters the accumulator. The forward movement of a rack bar into the accumulator causes its forward end to engage the jack 16 and to rock the jack toward the right, Fig. 1, so as to trip or release it from the detents 27 which hold it in elevated position, with the result that the jack drops and thereby rotates the bell-crank arm 39 to the left, Fig. 4, causing the nose 40 thereon to bear against the cam 41. The forward movement of a rack bar sets instrumentalities for operating all plates 3 of the rack bars to the right of the former, so that said plates will, also, be moved forwardly upon operation of the main operating element of the machine, whereby all plates 3 to the right of the left-hand adjusted or depressed finger piece or sector will be caused to enter the accumulator sufficiently to extend over the jack 16.

The operation of the main operating element of the machine causes the shaft 42 to rock counter-clockwise, Fig. 4, whereby the cam 41 presses against the nose 40 of the bell-crank arm 39 and causes the bell-crank to rock clockwise, with the result that the bell-crank is caused to raise the jack 16, which, in turn, operates to raise the adjacent ends of the rack bars 1 and the associated plates 3. These rack bars, however, are not at this time raised sufficiently to cause the rack teeth 6 to engage the toothed actuating wheels 32, although the plates 3 are at this time raised sufficiently to lift their respective latches 59, which then release or unlock their corresponding members 43, permitting the latter to be pulled to the right, Fig. 1, by their respective springs. Such movement of each member 43 causes that member to operate upon and turn its respective printing wheel so as to bring its zero type face 35 into printing position, further movement of such member causing its projection 46 to be pulled out of engagement with the notch 47 in the printing wheel, and this projection is held out of the path of the printing wheel until the clearing operation takes place. As these members normally hold the respective printing wheels in such position that the zero type faces thereon are not in printing position, the printing of a total will not cause zeros to be printed to the left of the left-hand digit of the total, as each printing wheel to the left of the left-hand digit remains in normal position. Lifting of the rack bars 60 and their associated plates 3 causes the hooks 7 on said plates to lift the arms 9 carrying the hooks 12, the latter being thereby caused to engage the rear side of the jack and the jack then acts as a lock to prevent such rack bars as have not been actuated

from being actuated until all the actuated bars have been restored to initial position. After the printing wheels have been rotated to present their zero type-faces to the printing position, the further rotation of the cam 70 41 rocks the bell crank further clockwise and thereby causes it to lift the jack higher until it reaches its initial position, the rack bars being then elevated sufficiently to engage the rack teeth 6 thereon with the respective actuating wheels 32. Hence, when the rack bars and their associated plates are restored to initial position, the actuating and printing wheels will have been rotated in a clockwise direction Fig. 1. Reverse 80 movement of the main operating element of the machine rotates the shaft 42 clockwise, whereby the cam 41 returns to normal position and leaves the bell crank in its initial position. 85

I claim:

1. In a calculating machine, the combination of a set of bars, an accumulator embodying a set of printing wheels each bearing a zero type face, means for normally holding the zero type face of each accumulator wheel in non-printing position, and means controlled by said bars for causing the accumulator wheels to turn to zero printing position. 90

2. In a calculating machine, the combination of a set of bars, an accumulator embodying a set of printing wheels each bearing a zero type face, a member engaging each wheel to hold it with its zero type face in non-printing position, and a latch co-operative with each member and releasable by its respective bar. 100

3. In a calculating machine, the combination of a set of bars, an accumulator embodying a set of printing wheels each bearing a zero type face, a member engaging each wheel and having a normal tendency to turn the same to zero printing position, and a latch controlling each member and releasable by its respective bar. 105

4. In a calculating machine, the combination of a set of bars, a set of co-operative plates, an accumulator embodying a set of printing wheels each bearing a zero type face, members co-operative with said wheels to normally hold them in non-printing position and having a tendency to turn such wheels to zero printing position, and latches co-operative with said members to normally prevent operation thereof and releasable by said plates. 115

5. In a calculating machine, the combination of a set of bars, a set of co-operative plates, an accumulator embodying a set of printing wheels each bearing a zero type face, members co-operative with said wheels to normally hold them in non-printing position and having a tendency to turn such wheels to zero printing position, a jack for 125

such rack bars as have not been actuated 130

raising said plates, and means normally preventing operation of said members and releasable by the raising of said plates.

6. In a calculating machine, the combination of a set of bars, a set of coöperative plates, an accumulator embodying a set of printing wheels each bearing a zero type face, members coöperative with said wheels to normally hold them in non-printing position and having a tendency to turn such wheels to zero printing position, latches having laterally turned ends resting upon the tops of the respective plates and normally preventing operation of said members, and means for raising said plates to disengage said latches from said members.

7. In a calculating machine, the combination of a set of reciprocatory bars, a complemental set of relatively shiftable plates, an accumulator embodying a set of wheels operative by said bars, and means for preventing subsequent operation of additional bars until after such bars as have been actuated are restored to initial position.

8. In a calculating machine, the combination of a set of reciprocatory bars, a complemental set of relatively shiftable plates, an accumulator embodying a set of wheels operative by said bars, means for setting said bars in coöperative relation to said wheels, and devices carried by said plates for locking such means from subsequent operation.

35 9. In a calculating machine, the combination of a set of reciprocatory bars, an accumulator embodying a set of wheels operative by said bars, a jack releasable by said bars for setting the same in operative relation to said wheels, and means for locking said jack to prevent subsequent actuation of additional bars.

10. In a calculating machine, the combination of a set of reciprocatory bars, a complemental set of relatively shiftable plates, an accumulator embodying a set of wheels operative by said bars, a jack releasable by said bars for setting the same in operative relation to said wheels, and means carried by said plates for locking said jack to prevent subsequent actuation of additional bars.

11. In a calculating machine, the combination of a set of reciprocatory bars, a complemental set of relatively shiftable plates, an accumulator embodying a set of wheels operative by said bars, a jack for setting said bars in operative relation to said wheels, hooks for locking said jack, and means car-

ried by said plates for engaging said hooks with said jack.

12. In a calculating machine, the combination of an accumulator embodying a set of printing wheels each provided with a peripheral notch and bearing a zero type face, a member associated with each wheel and having a terminal engagement in the notch therein to hold said wheel with its zero type face in non-printing position, and means for shifting each member in one direction to turn its respective wheel to zero-printing position.

13. In a calculating machine, the combination of a set of bars, an accumulator embodying a set of printing wheels each provided with a peripheral notch and bearing a zero type face, a member associated with each wheel and having a terminal engagement in the notch therein to hold said wheel with its zero type face in non-printing position, a latch controlling each member and releasable by its respective bar, and means for shifting each member in one direction, when released, to turn its respective wheel to zero-printing position.

14. In a calculating machine, the combination of an accumulator embodying a set of printing wheels each provided with a peripheral notch and with a zero type face, and a member associated with each wheel and having a terminal projection engaged with the notch therein to normally hold said wheel with its zero type face in non-printing position, said members having a tendency to turn said wheels to zero-printing position.

15. In a calculating machine, the combination of a set of bars, an accumulator embodying a set of printing wheels each bearing a zero type face, members coöperative with said wheels to normally hold them with their zero type faces in non-printing position, each of said members having a shoulder, a latch coöperative with each member and having a shoulder engaged with the shoulder thereon, said latches being releasable by said bars, and means for automatically shifting said members endwise when released to turn the respective wheels to zero-printing position.

In testimony whereof I hereunto affix my signature in the presence of two witnesses.
